UNITED STATES PATENT OFFICE.

CHARLES ERNEST JONES, OF CHICAGO, ILLINOIS.

CHANDELIER APPARATUS.

1,290,569.

Specification of Letters Patent.

Patented Jan. 7, 1919.

Application filed September 30, 1918. Serial No. 256,221.

To all whom it may concern:

Be it known that I, CHARLES ERNEST JONES, a citizen of the United States, and resident of Chicago, county of Cook, and 5 State of Illinois, have invented certain new and useful Improvements in Chandelier Apparatus, of which the following is a specification, and which are illustrated in the accompanying drawings, forming a part 10 thereof.

The invention relates to chandeliers, and contemplates apparatus which may be used with different glassware varying widely both in size and shape, and which permits of a 15 considerable variation both in the number and the arrangement of the lights employed. The invention further contemplates that several variations may be made in the manner in which the chandelier is supported.

20 The object of the invention is to provide chandelier apparatus which is substantially standard for chandeliers of a great variety of styles and sizes.

In the accompanying drawings—

25 Figure 1 is a perspective view showing apparatus provided by the invention embodied in the construction of a chandelier comprising a single pendent support, an undrilled bowl with outturned marginal 30 flange and interior lights;

Fig. 2 is a sectional view showing the apparatus embodied in the construction of a similar chandelier comprising a centrally drilled bowl with inturned marginal flange, 35 another form of support being indicated by dotted lines;

Fig. 3 is a detail perspective view showing an arrangement which may be employed with undrilled bowl, exterior ornament and 40 overhanging upturned lamp brackets; and

Figs. 4, 5 and 6 are detail sectional views showing further modifications, an additional modification being shown in dotted lines in Fig. 5.

45 The apparatus provided by the invention comprises as its principal element a central spider, represented at 10 in Figs. 1 and 2. This spider is shown in Fig. 1 as having four arms 11, 12, 13, 14, but three or more arms 50 may be provided, and the larger number of arms will preferably be employed when upstanding rim lamps, as 15 (Fig. 5), or overhanging exterior lamp brackets, as 16 (Fig.

3), or 17 (Fig. 5) are used in conjunction with a large glass bowl.

The hub, as 18, of the spider 10 has a central threaded aperture, and when a single pendent support, as the chain indicated at 19 (Fig. 1), is used, a tubular rod 20 is screwed into the hub 18 from above and extends upwardly therefrom through an ornamental husk 21. In this form of chandelier the upper end of the rod 20 may be united with a ring 22 which in turn connects with the chain 19. This arrangement 65 has the advantage that only a relatively short length of the chain 19 is required to provide the necessary support. When inclined chains, as 23 (Fig. 2), 24 (Fig. 4), or 33 (Fig. 6) are employed, these chains 70 extend to points adjacent the margins of the bowl, and the central upright rod 20 and husk 21 may be omitted.

In event a centrally drilled bowl, as 25 (Fig. 2) is used, a vertical rod 26 is screwed 75 into the hub 18 of the spider 10 from below the same, and extends to and through the bottom of the bowl, which is secured thereto by clamping nuts 27, 28, and intermediate washers 29, 30. As usual the washer 29 upon 80 the inside of the bowl will be held from direct contact with the glass by a felt washer 31, and the washer 30 upon the outside of the bowl will be of an ornamental form, while an additional ornament, as 32, may be 85 attached to the exterior clamping nut 30. A drilled bowl, as 25, may be attached to the spider 10 when the latter is supported through the central upright rod 20, or when the spider is supported by the inclined 90 chains indicated by dotted lines at 23 (Fig. 2). In event the upright rod 20 is used, the hub 18 is desirably provided with a lateral outlet 34 for the electric conductors, 95 as 35.

In all cases the arms, as 11, 12, 13, 14 of the spider 10 are each formed at their outer ends with an offset tubular head 36. The head 36 of each arm of the spider is thus constructed for adjustable connection with 100 an extension rod 37. Each extension rod 37 slides through the bore of the head 36 of the corresponding arm of the spider, and is secured in adjusted position by a set screw 38. The head 36 of each arm of the spider 10 is 105 preferably also threaded upon the exterior

to receive a clamping nut 39, by which a lamp bracket 40 is secured in place. The lamp brackets 40 are, of course, used only for interior lights, as 41, and usually such brackets will only be applied to selected arms, as 11 and 13, of the spider.

In all of the several arrangements illustrated in the drawings, hook-shaped bracket pieces, as 42 (Figs. 1, 2 and 4), 43 (Figs. 3 and 5) or 44 (Fig. 6) are rigidly mounted upon the extension rods 37 at their outer ends. However, in event a centrally drilled bowl, as 25, is used and no inclined supporting chains, as 23, exterior lights, as 15, or exterior lamp brackets, as 16 or 17, are required, the function of the extension rods 37 is merely to steady the bowl, and for this purpose the outer ends of the rods may be directly engaged with the bowl upon the inside of the same. When the bowl, as 45 (Figs. 1, 3, 5 and 6) has an outturned marginal flange 46, the bracket pieces 42, 43 or 44 will have hooked engagement with the said flange and thus support the bowl. With this arrangement the application of an ornament, as 49, to the outside of the bowl is readily accomplished upon the outer end of the corresponding bracket piece, as 43 (Fig. 3). If desired the ornament 49 may be secured to the bracket piece, as 43, by a screw 50.

When the flange, as 47 (Fig. 2) of the bowl is inturned the bracket pieces, as 42, may have supporting engagement with the bowl upon the inside, under the said flange, and no other support for the bowl is required. In event the bowl, as 48 (Fig. 4) is drilled near its rim, screw-eyes, as 51, may be mounted in the bowl, and these screw-eyes 40 will have hooked engagement with the corresponding bracket pieces, as 42.

Each of the bracket pieces 42 and 43 is preferably formed with a hump 52, for engagement with the end of the chain 23 or 24, when inclined chains are used. If it is desired to have the inclined chains, as 33 (Fig. 6) extend to the plane of the outer edge of the bowl, bracket pieces of the form shown at 44 may be used upon the ends of

the extension rods 37. As shown, the bracket 50 piece 44 is formed with an upstanding chain hook 54.

When the chandelier includes upstanding rim lamps, as 15, or overhanging brackets, as 16 or 17, for exterior lights, bracket pieces 55 of the form shown at 43 (Figs. 3 and 5) are used upon the ends of the extension rods 37. The bracket pieces 43 are each provided with a threaded socket 53, into which the base of the rim lamp 15 or the inner end of the lamp bracket 16 or 17 is fitted.

While bracket pieces, as 43, of the form provided with the threaded socket 53 are shown as being used only in the several arrangements illustrated in Figs. 3 and 4, it 65 will be understood that this form of bracket piece may be used in place of the bracket piece 42 in each of the arrangements illustrated in Figs. 1, 2 and 4. It is therefore obvious that either rim lamps, as 15, or overhanging lamp brackets, as 16 and 17, may be provided, whether the chandelier is hung from a single central support or from inclined chains and whether the bowl is centrally drilled, drilled near its rim, or is un- 75 drilled.

I claim as my invention—

1. A chandelier comprising a spider having a plurality of equally spaced adjustably extensible radial bowl-engaging arms, an 80 upwardly facing central socket for detachably receiving the lower end of a pendent hanger, a downwardly facing central socket for detachably receiving the upper end of a pendent bowl support, and an intermediate 85 lateral outlet opening for the lighting conductors.

2. In a chandelier, in combination, a spider having a plurality of equally spaced adjustably extensible radial arms, a bowl-supporting hook rigidly mounted upon the outer end of each arm of the spider, each bowl-supporting hook being formed with a socket for receiving a lamp bracket, and means for connecting the spider to a central 95 pendent support.

CHARLES ERNEST JONES.
